UNITED STATES PATENT OFFICE.

ADOLPH F. MEYER, OF ST. PAUL, MINNESOTA.

SPILLWAY.

Application filed January 5, 1925. Serial No. 615.

To all whom it may concern:

Be it known that I, ADOLPH F. MEYER, a citizen of the United States, resident of St. Paul, in the county of Ramsey and State of Minnesota, have invented certain new and useful Improvements in Spillways, of which the following is a specification.

This invention relates to an improved spillway as well as to the novel method of 10 designing and building the spillway.

At present practically all spillways are built according to the ogee profile and with a curvature to cause the overfalling water to be discharged in a horizontal direction.

15 The fillet or "bucket" at the toe of the dam or spillway is usually provided to assure this horizontal deflection of the discharged sheet for the estensible purpose of protecting the bed of the stream against undercutting and erosion at the lower end of the toe particularly when severe floods are passed. In such present spillway designs, scour and uplift under the apron are common sources of trouble. Uplift occurs when 20 the tail-water below the spillway (the terms overfall dam, weir and dam with crest gates are to be understood as included in the term "spillway") is not sufficiently deep to prevent the tail-water from being pushed 25 downstream away from the spillway so that the overfalling water is permitted to move swiftly, in a thin sheet, over at least a portion of the apron. Scour occurs whenever the excess energy of the overfalling 30 water is not sufficiently destroyed before this water reaches the erodible river bed. If the tail-water is sufficiently deep, there is no uplift but the tendency toward scour persists for long distances downstream from 35 present spillway structures, which necessitates long and expensive aprons, cribs, mattresses, riprap or other forms of river bed protection. The overfalling water follows the profile of the present-day spillway and, 40 since the line of action of the dynamic pressure is much lower than the line of action of the static back-pressure of the tail-water, a couple is formed causing rotation and hence the formation of a large eddy on top 45 of the swiftly moving water. In this case the surface currents beyond the spillway are backward for a considerable distance downstream; high velocities usually persist in the deeper currents until beyond the end of the 50 apron and scour continues, whereby expensive repairs are necessitated.

Among those skilled in the art to which this invention relates there appears a present tendency of opinion in opposition to the usual bucket or curved base of the fore 60 slope which is so pronounced a feature in present spillways because the destructive velocity of the overfalling water is conserved by the smooth curved surface of the bucket, and resort has been had, for example, to 65 baffles fixed upon the curved slope, and an attempt has been made to drop the water more nearly vertically rather than to shoot it away from the spillway in a horizontal direction. 70

In this novel invention, use is made of what may be termed a "hollow bucket", that is, the bucket or curved face of the fore slope at the downstream toe of the spillway, 75 is recessed or hollowed to provide a basin whose dimensions are substantially correlated with the height of the dam, the amount of overflow, and the natural depth of the tail water below the dam. The spillway is constructed preferably so as to lead 80 the water, just before it enters the pool provided by the hollow bucket, in as nearly a vertical direction as its initial horizontal velocity and the structural features of the design permit. By doing so, the dynamic pressure of the overflowing water is exerted more nearly directly in opposition to the static pressure of the pool. In consequence, 85 the swiftly moving water is quickly slowed up, the surface eddy is greatly reduced in 90 size, and the water acquires a downstream direction of motion throughout the full depth of the natural stream within a short distance from the toe of the dam. 95

A feature of the novel invention, which it is desirable to use in most spillways, resides in the shaping of the hollow bucket to provide a portion which extends in an upstream direction underneath the front slope or face of the spillway. This bucket 100 portion permits the formation of a back eddy behind the swiftly flowing water, so that the overfalling water is attacked on the underside and more rapidly retarded. 105

Another novel feature, above suggested, consists in the proper dimensioning of the hollow bucket in correlation with the energy possessed by the overfalling water as it enters the bucket substantially at the elevation of the center of gravity of the tail-water. At the foot of the fall the swiftly moving water is capable of exerting a 110

continuous pressure in the direction of its motion equal to its mass times its velocity. This is known as the dynamic pressure of the flowing water. In addition, this water exerts a static pressure in every direction proportional to its depth. This latter pressure of the swiftly moving water is usually very small in proportion to the former. To slow up the swiftly moving water and to 10 destroy its excess energy so that it will flow down the natural channel again at the same depth and velocity as it did before the dam was built, it is necessary to apply to it a static back-pressure at least substantially 15 equal to the dynamic pressure plus the static pressure of the swiftly moving water minus the residual dynamic pressure which the water possesses in a downstream direction after it has been slowed up. The greater 20 the static back-pressure provided and the more effectively it is applied to the swiftly moving water, the more quickly will that water be robbed of its excess energy. The 25 depth of water which provides this necessary static back-pressure is herein designated by the capital letter "D" and is made the principal basis for the dimensioning of the novel hollow bucket. Hence, for sake of 30 clarity and brevity, such letter "D" is, in the specification and claims, employed to designate and specify such linear dimension.

The object therefore of the invention is to provide an improved spillway and method 35 of designing and building the same.

Other objects of the invention will appear from the following description and the accompanying drawings and will be pointed out in the annexed claims.

40 In the accompanying drawings there have been disclosed a series of structures designed to carry out the objects of the invention but it is to be understood that the invention is not confined to the exact features shown as 45 various changes may be made within the scope of the claims which follow.

In the drawings:

Figure 1 is a vertical sectional view 50 through a spillway constructed in accordance with the invention, the spillway being of the hollow type and of medium or average height;

Figure 2 is a vertical sectional view of 55 a low solid-type of spillway embodying the invention and adapted to a very large discharge;

Figure 3 is a view of a spillway similar 60 to that shown in Figure 1 but of the solid type and adapted to a larger discharge;

Figure 4 is a similar view through a solid 65 spillway of the high type showing the invention as applied thereto;

Figure 5 is a solid spillway of the type 70 employing gates and adapted to a relatively 75 large discharge;

Figure 6 is a vertical sectional view of a form of the novel spillway showing the hollow bucket reduced to its minimum practicable dimensions; and

Figure 7 is a similar view with the novel 70 undercut omitted.

The application of this novel invention to several different structures is shown in the drawings in order to aid in clearly explaining the invention in such full, concise and 75 exact terms as to enable any person skilled in the art to which it appertains, to carry out the method and to construct and use spillways, embodying the invention.

The invention is shown in Figure 1 as 80 applied to a well-known form of dam or spillway of the hollow type which is preferably of concrete construction, desirably steel-reinforced, as this is the most practical material for construction and one with which those skilled in this art are most familiar, although it is to be understood that other material may be used.

The base 9 of the spillway has an upstream deck at its heel 11 with its lower portion 12 substantially vertical while the major portion 13 thereof is upwardly inclined in a downstream direction to the crest 14. The upper portion of the apron or fore slope 15 of the spillway has, in profile, the common ogee curve. At the toe or downstream end of the fore slope, it is the usual practice to provide a solid curved fillet or bucket which, as above stated, causes the overfalling water to be discharged in a horizontal direction for the ostensible purpose of protecting the stream-bed against undercutting and erosion at the lower end of the toe.

100 In this novel invention there is provided a recessed or hollowed bucket 16 at the downstream toe and such hollow bucket extends substantially the whole length of the spillway, that is, across the stream-bed occupied by the spillway. The overfallen water may 105 therein form a pool at the spillway toe and the static pressure thereof opposes the dynamic pressure of the overfalling water as it enters the pool with the result that the swiftly moving water is suddenly slowed up and the water acquires a downstream direction of motion throughout the full depth of the natural stream within a short distance of the spillway toe.

110 While the hollow bucket may be a separate structure, it is preferable to construct it as an integral part of the spillway strengthening it with a plurality of spaced buttresses or cross-walls 10. In a spillway of this type, these buttresses or cross-walls 10 are placed 115 opposite the usual cross-walls 20 of the main spillway structure. Among the advantages of integral construction are a greater ease in designing or laying-out, a reduction in expense of construction, the spillway 120

125 four-

dation is widened, a more uniform distribution of foundation pressures is attained, and greater stability against sliding is assured. The bucket has a base or bottom 17, a downstream wall 18, downstream rim 19, and an upstream wall 21. From the downstream end of the rim 19, an apron 22 may be extended and this may be integral with the bucket or not, as desired, although it is here 10 shown as the latter. It may be noted that the apron 22 is shown in the drawings as being unusually short for the spillway illustrated and such showing is intentional as the employment of the novel hollow bucket with 15 its water-slowing function permits the use of such inexpensive short apron.

The novel undercutting of the fore slope of the spillway is also shown in Figure 1 wherein the lower portion of the fore slope 20 15 is re-entrantly designed to provide a recess 23 forming an upstream continuation of the hollow bucket 16. Thus, this bucket portion or recess 23 extends upstream underneath the fore slope or downstream face of 25 the spillway. The result of such shaping of the bucket is to cause the formation of a back eddy behind the water swiftly descending into the bucket pool. Hence, the over- 30 falling water is attacked on the underside and is more rapidly retarded and the greater the thickness of the overfalling water, the more valuable becomes the undercut recess 23.

In the spillway embodying the invention, 35 the fore slope is shaped to lead the overfalling water, just before it enters the hollow bucket pool, in as nearly a vertical direction as its initial horizontal velocity and the structural features of the design permit. 40 The purpose is to cause the dynamic pressure of the overfalling water to be exerted more nearly directly in opposition to the static pressure of the pool.

While the precise dimensions of this novel 45 hollow bucket may be varied for different installations, the dimensions of a particular bucket for a given installation are substantially correlated to the height of the selected dam or spillway, the amount of overflow and 50 the natural depth of tail-water below the dam. In this art these three factors (height, amount and depth) for any given installation, are always determined as accurately as possible in advance of the designing of the 55 dam or spillway to be constructed. Likewise one skilled in this art, may quickly and easily determine with accuracy for any proposed project the depth of tail-water which 60 will provide the static back-pressure necessary to destroy the excess energy of the overfalling water so that it will flow down the natural channel below the fall at the same depth and velocity as it naturally does without 65 the projected dam or spillway. Such predetermined depth of tail water is herein

specified by "D" for sake of clarity and conciseness. Incident to the determining of the dimension "D" there is also determined the thickness of the overfalling sheet of water assuming that it has had an unobstructed 70 fall to substantially the level of the center of gravity of the tail-water. Such predetermined thickness will be herein specified by "T". The effective dimensioning of the hollow bucket is principally based upon 75 such dimensions "D" and "T." Therefore, in carrying out this novel method of designing a spillway for a particular project or installation, there is first determined as closely as possible the relation between the 80 volume of water discharged, the drop thereof, and the natural water level below the dam for all flood discharges. By "all" flood discharges is meant not only the maximum 85 flood discharge which the spillway must accommodate but also lesser flood discharges which sometimes govern at least some of the dimensions of the novel hollow bucket. The dimensions "D" and "T" are then determined for the various flood conditions. 90 After determination of such basic dimensions, the hollow bucket is proportionately 95 designed.

In the preferred form of hollow bucket, its downstream width from the median 95 plane of the overfalling water during the maximum flood discharge is substantially equal to said dimension "D" and never less than substantially one and a half times the thickness "T" of the overfalling water during maximum flood discharge as it enters 100 the hollow bucket. The top of the hollow bucket at the upstream side is below the level of the tail-water during maximum flood conditions and, particularly for the purpose 105 of determining the dimension "T" is preferably taken as substantially at the level of the center of gravity of the tail-water during maximum flood conditions. The bottom 17 of the bucket must be below the downstream 110 rim 19 a distance greater than the thickness or width "T" of the overfalling water during maximum flood discharge as it enters the hollow bucket. The downstream rim of 115 the bucket is designed to be below the level of the tail-water a distance at least equal to the dimension "D". As it is preferred to employ the undercut recess continuation of the bucket in installations having 120 a relatively large overflow, such undercut recess is designed to extend in an upstream direction from the median plane of the overfalling water a distance less than the dimension "D". In spillways where such 125 undercut continuation is provided, it is preferable to give the bottom of the hollow bucket a dimension equal to substantially twice "T", exclusive of the continuation underneath the downstream face of the 130 spillway.

In the form of spillway shown in Figure 2, there is graphically illustrated the solid type of spillway adapted to discharge a relatively larger volume of water at a lesser drop than is shown in Figure 1 and there is also suggested the shape of the novel hollow bucket resultant from the application thereto of the teaching of this invention.

Figure 3 illustrates a solid type spillway which is adapted to a lesser volume and a greater drop than is shown in Figure 2 but to a larger volume and only a slightly greater drop than is shown in Figure 1. The comparison of the shapes suggested of the hollow buckets respectively illustrated will aid those skilled in the art in visualizing readily the results obtained by the application of this invention to such variant forms of spillways.

The solid type of spillway is also shown in Figure 4 as well as in all the remaining figures. This particular figure illustrates a relatively high spillway and, from a comparison of the undercutting extensions of the buckets in the different explanatory views, it will be noted that as the height of the drop increases, the undercut portion is reduced because with increase of drop the undercut feature is not so effective and because structurally it becomes less and less desirable.

The form shown in Figure 5 is of that known as the gate type and it may be noted in this connection that, while the gate is shown as entirely open, the hollow bucket would have the same desirable action if the gate were partially closed. The principal dimension "D" for this type of bucket should preferably be computed upon the assumption that only part of the gates will be opened a large amount thus discharging a large volume of water at one portion of the width of the spillway without a proportionate raising of the depth of tail-water which will thinly spread out over the downstream river bed. Under such conditions the downstream rim of the bucket must be placed relatively lower than if all of the gates were opened the same amount. In other words, when designing such a hollow bucket, there will initially be determined the depth of tail-water over the rim which will provide the above specified static back pressure when only part of the gates are opened. Such dimension "D" so obtained will obviously necessitate lowering the rim of the bucket below an elevation obtained from a computation from conditions obtaining when all of the gates are opened.

Figures 6 and 7 are more particularly useful as illustrative of the novel hollow bucket spillway wherein the bucket is reduced substantially to its minimum practicable dimensions while still carrying out the objects of the invention. It will be noted that Figure

7 omits the undercut feature of the bucket and as a result the cross-wall or buttress 10 is also omitted. On account of the upward currents on the downstream side of the novel hollow bucket 16, logs and other débris are deflected upward and the tendency for such débris to strike the downstream wall 18 of the hollow bucket is minimized. When used as a part of the hollow bucket, the buttress 10 also acts to deflect logs, trees, ice and other large floating débris, downstream. Such débris, however, can not long lodge in the small eddy next to the dam as it will soon be caught by the downstream currents. Where large quantities of logs must be passed over a spillway dam instead of through sluices specially provided for that purpose, the hollow bucket, with slightly increased cost, may advantageously be widened downstream, dependent upon the length of logs floated in the given stream.

Having thus described my invention what I claim as new and desire to secure by Letters-Patent, is:

1. In a spillway of the adherent nappe type, a hollow bucket having a portion extending upstream underneath the downstream face of the spillway.
2. In a spillway of the adherent nappe type, a hollow bucket having a portion extending upstream underneath the downstream face of the spillway and the bottom of the bucket being below the level of the downstream bed.
3. In a spillway of the adherent nappe type, a hollow bucket having its bottom below the level of the downstream bed and its downstream rim below the level of the tail-water a distance at least substantially equal to the specified dimension "D" for all discharges of said spillway.
4. In a spillway of the adherent nappe type, a hollow bucket having a portion extending upstream underneath the downstream face of the spillway and said portion upwardly terminating below the level of the tail-water corresponding to maximum flood discharge of the spillway.
5. In a spillway of the adherent nappe type, a hollow bucket dimensioned to produce a surface eddy in the overfallen water above the bucket and to restrict the surface eddy substantially to the overfallen water above the bucket whereby said eddy is prevented from extending downstream materially beyond the downstream rim of the bucket.
6. In a spillway of the adherent nappe type, a hollow bucket at the downstream toe of the spillway, the bottom of the bucket being below the natural level of the downstream river-bed, and reinforcing means connecting the bucket with the front of the spillway to render the bucket structurally and functionally integral with the spillway.

whereby some of the water pressure against the back of the spillway is carried to the foundation through said hollow bucket.

7. In a spillway of the adherent nappe type, a hollow bucket at the downstream toe of the spillway, the bottom of the bucket being below the natural level of the downstream bed, and a plurality of reinforcing members connecting the bucket with the front of the spillway making said bucket an integral part thereof whereby some of the water pressure against the back of the spillway is carried to the foundation through said hollow bucket.

15. 8. In a spillway of the adherent nappe type, a hollow bucket at the downstream toe of the spillway, said bucket having a portion extending upstream underneath the downstream face of the spillway, and a plurality of reinforcing members connecting the bucket with the front of the spillway making said bucket an integral part thereof whereby some of the water pressure against the back of the spillway is carried to the foundation through said hollow bucket.

20. 9. In a spillway of the adherent nappe type, a hollow bucket adjacent its downstream toe and extending substantially the length of the spillway and a plurality of reinforcing members connecting the bucket and front of the spillway making said bucket an integral part thereof whereby some of the water pressure against the back of the spillway is carried to the foundation through said hollow bucket.

25. 10. In a spillway of the adherent nappe type, a hollow bucket adapted to confine the surface eddy to the overfallen water above the bucket and the bottom of the bucket having a depth below its downstream rim at least substantially equal to the specified dimension "T" for maximum flood discharge

and the downstream width of the bottom of the bucket being at least equal to substantially twice the specified dimension "T" for 45 maximum flood discharge, and said bucket having its downstream rim below the level of the tail-water a distance at least equal to the specified dimension "D" for all discharges of said spillway.

50. 11. In a spillway of the adherent nappe type, a hollow bucket adapted to confine the surface eddy to the overfallen water above the bucket and the bottom of the bucket being a depth below its downstream rim at least substantially equal to the specified dimension "T" for maximum flood discharge and the downstream width of the bottom of the bucket being at least equal to substantially twice the specified dimension "T" for 55 maximum flood discharge, said bucket having a portion extending upstream underneath the downstream face of the spillway, and also having its downstream rim below the level of the tail-water a distance at least 60 equal to the specified dimension "D" for all discharges of said spillway, and a plurality of reinforcing members connecting the bucket with the front of the spillway making said hollow bucket an integral part 65 structurally and functionally of said spillway structure.

70. 12. A monolithic spillway having an adherent nappe face for the discharge of the overfalling water, said spillway being 75 formed with an integral hollow bucket at the downstream toe of the spillway and with the bottom of the bucket below the natural level of the downstream river-bed, and said bucket having a portion extending upstream underneath the downstream face of the spillway.

75. In witness whereof, I have hereunto set my hand this 29th day of December 1924.

ADOLPH F. MEYER.
